UNITED STATES PATENT OFFICE.

DANIEL MCFARLAN MOORE, OF NEWARK, NEW JERSEY, ASSIGNOR TO GENERAL ELECTRIC COMPANY, A CORPORATION OF NEW YORK.

VACUUM-TUBE ELECTRIC-LIGHTING APPARATUS.

1,032,928.

Specification of Letters Patent. Patented July 16, 1912.

Application filed April 16, 1908. Serial No. 427,368.

To all whom it may concern:

Be it known that I, DANIEL MCFARLAN MOORE, a citizen of the United States, and a resident of Newark, in the county of Essex and State of New Jersey, have invented certain new and useful Improvements in Vacuum-Tube Electric-Lighting Apparatus, of which the following is a specification.

My invention relates to that form of electric lighting apparatus or installation in which vacuum tubes of considerable length are employed as in the system of vacuum tube lighting devised by me and now in commercial operation. As usually operated the tubes of this system are extended over the areas to be lighted and the gas or vapor within the tube is excited to luminosity by the application of alternating or varying electric currents which have to be of a tension or electromotive force increasing with the length of the tube employed. If a straight tube of very great length having its electrodes at opposite ends and provided with a single source of electromotive force at one end be used, it is necessary to connect the electrodes at the opposite end of the tube by a wire through which a very high tension current flows.

It has been customary in the above system of lighting to incase the source of high tension current in a danger proof box at one end and protect the wire leading to the other end by a suitable conduit. This works well for tubes up to a certain length, but when it is desired to use extremely long tubes, the tension necessary to operate these long tubes becomes so high that troubles are very liable to arise with the transformers and the breaking down of the insulation and therefore fire-risks and danger to life are greater. To avoid running a high tension wire to the opposite end of the tube, the tube itself has been formed as a loop thus bringing the two ends of the tube together in the same box. This, however is open to the same serious objections as the straight tube when a long length is employed, as the use of the extremely high tension necessary creates considerable trouble in the danger proof box as set forth.

One object of my present invention is to remove the difficulties above alluded to and also the fire risk and danger to life and

property which might arise from the employment of these very high tensions, and to these ends my invention consists mainly in the utilization of a divided source of electromotive force for supplying current of the necessary tension to the tube. For instance, if it is necessary to supply 20,000 volts to a tube of a certain length, by practising my present invention, it would merely be necessary to supply 10,000 volts to each end of the tube and connect the respective sources of such electromotive force in series or parallel.

Another object of my invention is to simplify the apparatus by reducing the size of its component parts which I accomplish by employing generating apparatus at both ends of the tube.

My invention consists further in utilizing the well-known fact that any circuit has a zero point at an equal distance from the opposite poles and by utilizing this fact, the employment of return wires of high tension is avoided.

This part of my invention consists in connecting the points of zero potential of the sources of electromotive force to each other, which connection will therefore be neutral and at zero potential. If desired, this neutral wire or connection might be grounded or the zero points of each source might be connected to ground in which case no return wire is employed, the ground forming the return for the circuit. To obtain the point of zero potential of the respective transformers which form the source of electromotive supply, the primary and secondary windings are connected together.

My invention is more particularly set forth in the subjoined description taken in connection with the accompanying drawings and then specified in the claims.

In the drawings, Figure 1 illustrates in skeleton the usual arrangement of a vacuum tube lighting system as at present employed with a straight tube and Fig. 2 illustrates the usual arrangement with a loop tube. Fig. 3 shows in skeleton one of the improved arrangements or installations embodying my present invention. Fig. 4 is a skeleton diagram of the arrangement shown in Fig. 3. Fig. 5 and following figures show in diagram other arrangements or modifications of my invention.

Referring to Fig. 1, 2 is a vacuum tube furnished, preferably, with the usual interior electrodes 3 by which energy is transferred to and passed through the contained gas or vapor. 4 is a protective casing from which said tube extends, one terminal of said tube being located in said casing wherein also is located, preferably, the source of electrical energy which may be the secondary 5 of a transformer. At 4' is another protective casing sealing the remote end of the tube and similar to 4. 6 is a wire conduit or protective tube extending from casing to casing and containing the return wire 7 or connection 7 of the system, while 8 is any suitable supporting fixture for the intermediate portions of the tubes 6 and 2. The primary of the transformer is indicated at 9, while 10, 10' are the supply wires by which alternating or other electric currents are supplied to and pass through the primary 9. This figure shows one old form or arrangement of the tube, but in other arrangements heretofore employed, the end 25 of the tube, terminating in 4' might be brought around into the casing 4 as shown in Fig. 2.

In the system shown in Figs. 1 and 2, it is obvious that the greater the length of the tube and the greater the consequent potential or electromotive force required for operating the same, the greater will be the fire risk or danger due to the presence at different points of the system of high differences 35 of potential.

My present invention consists of a system by which the length of the tube or the number of tubes running in series may be greatly increased without necessitating the employment of high tension return wires. One of the ways in which this may be accomplished is shown in Fig. 3. In this instance, the source of energy for supplying the tube is divided or otherwise stated consists of two separate sources operating as one to supply the tube with energy in series with one another. One of the sources is indicated as the secondary 5 of a transformer, while 5' indicates the other source or division of the source. I prefer to employ a neutral wire or connection 12 running from one source to the other and connected, preferably, also to the primaries 9, 9' of the two sources or divisions of source, as indicated 55 more clearly in the diagram, Fig. 4, but obviously this neutral wire might be dispensed with as illustrated in Fig. 13.

As shown in Fig. 3, the two sources are located, respectively, in the boxes 4, 4' or 60 may be otherwise located, as will be seen in some of the other figures. The return wire or connection 7 of the system, may run with the neutral wire or connection 12 through the conduit 6. The neutral connection may, if 65 desired, be composed of a ground formed by

grounding the intermediate or connecting wire of the primaries and secondaries at the point of zero potential thereof as illustrated in Fig. 13, or, if desired, the neutral wire and the ground connection may be both 70 employed. In other words, the neutral connection of my invention may consist of connecting wire 12, or a ground connection, or of both. In this particular arrangement, it will be seen that the primaries 5, 5' are in 75 series with one another over the neutral wire or connection, and that similarly the secondaries are in series with one another over such neutral wire or connection.

In the diagram, Fig. 4, I have shown in 80 addition the usual feed regulating magnet coil 13 employed for governing the admission of gas to the tube through a suitable valve and feed tube 14, as is now usual in this art. These, however, form no special 85 part of my present invention. As shown in Fig. 4, the transformer primaries are operated in series from the same pair of supply wires 10, 10', but it would be within my invention to operate said primaries from separate supply wires or from the same supply 90 wires in multiple. The arrangement shown in Fig. 4 has the advantage that the neutral wire 12 or the neutral connection forms also the series connection between the primaries 95 or other elements of the divided source or double source of energy.

Fig. 5 shows an arrangement wherein two tubes are arranged end to end or in series and supplied in series with one another from 100 the two secondaries operating as before in series. The neutral wire or connection may be grounded as before and a similar ground connection may be employed at the intermediate connection between the two tubes. 105 The neutral may form the third wire 15 of a three-wire system and in this, as in the prior instances, the tubes are supposed to be supplied with single phase currents. The two primaries are in series across a 110 volt system, the difference of potential between the extreme wires and the intermediate wire being however but 110 volts and each primary therefore being, in fact, operated on 110 volts. Each tube may have its 115 own means for feeding gas and each transformer may be in its own box, the boxes being located at extremes of the installation and the tubes being arranged end to end.

Fig. 6 shows a modification of this arrangement wherein the tubes are arranged parallel to one another and the source of energy or divided source is located at one terminal or at one point of the installation. The neutral wire or connection is indicated 125 as before by the numeral 12.

In the modification shown in Fig. 7, the arrangement is in general the same as indicated in Fig. 6, excepting that the divided source of energy has its elements located 130

remote from one another at or near the ends of the two parallel tubes. In Fig. 7, each primary or section of primary is supposed to be run on 110 volts and on the single phase system.

Fig. 8 illustrates the invention as carried out in the double-phase system, each primary being operated on its own phase, but the connections being otherwise substantially as in Fig. 7, otherwise the diagram is self-explanatory.

Fig. 9 shows two pairs of tubes, the two tubes of each pair being operated respectively by currents out of phase for the purpose of securing a steady light with low frequencies.

Fig. 10 shows three tubes as operated on a three-phase delta system, the transformers or section of transformers being in V.

Fig. 11 shows the three tubes operated on a three-phase star system, the transformers being in star and the neutral being grounded.

Fig. 12 illustrates a three-tube, three-phase delta system, the transformers being in T.

Fig. 13 illustrates the invention as carried out without employing a neutral wire, the points of zero potential of the two sources being grounded as shown, in which case the return is made through the ground.

Fig. 14 illustrates the invention as applied to two tubes arranged in close proximity to each other and provided with a single reflector 30. In this case, each tube is independent of the other, each being provided with its own sources of energy and each operated on a different phase and therefore the light from these tubes will not throw any image. A further advantage in this arrangement is that should one of the tubes cease to operate from any cause whatever, light will still be obtained from the other.

Obviously, my invention is not limited to connecting the windings of the transformers and connecting the neutral points to obtain the return circuit as one end of each secondary winding might be connected to ground, the return wire or neutral wire being replaced by the ground.

What I claim as my invention is:—

1. A vacuum tube lighting system operated by divided sources of energy working in series, as described, and located respectively at opposite terminals of the system and a neutral connection between the divisions of said source running from one terminal to the other as and for the purpose described.

2. In a vacuum tube lighting system, the combination of a divided source of energy consisting of one or more transformers, a tube or tubes in series supplied thereby, and a neutral connection between the transformer primaries and secondaries and run-

ning from one division of the source to the other.

3. In a vacuum tube lighting system, a divided source of energy whose elements operate the system in series but are located respectively at the terminals thereof combined with a neutral wire running from one to the other, as and for the purpose described.

4. In a vacuum tube lighting system, having tubes arranged in series, and provided with an intermediate ground connection, and a divided source of energy operating said tubes in series and having an intermediate neutral grounded wire running from one division to the other.

5. In a vacuum tube lighting system, a pair of tubes arranged side by side and having at one end of the system a divided source of energy operating the tubes in series and provided with a neutral wire or connection, as and for the purpose described.

6. A vacuum tube lighting system comprising a three-wire, single-phase system of supply conductors, two transformers located, respectively, at opposite ends or terminals of the installation and supplying the tube in series with one another, and a neutral wire or connection running from the terminals of both primary and secondary of the two transformers.

7. In a vacuum tube lighting system, a pair of vacuum tubes, a pair of transformers supplying said tubes respectively with currents of different phase, and a neutral wire or connection between transformer secondaries and primaries, as and for the purpose described.

8. In a vacuum tube lighting system, two pairs of vacuum tubes and two divided sources of electrical energy supplying said pairs with currents of different phase and provided with neutral wires or connections substantially as shown and described.

9. A vacuum tube lighting system having a translucent tube, the ends or terminals of which are located at a distance from one another and individual sources of energy located at the terminals respectively and joined by a direct connection independent of that through the tube.

10. A vacuum tube lighting system having a translucent tube provided with an individual source of energy at each end thereof and a ground connection from the point of said sources across which there is a zero difference of potential.

11. In a vacuum tube lighting system, a pair of independently operated tubes located in electrical relation to each other and operated by currents out of phase with each other.

12. A vacuum tube lighting system operated by two transformers, one located contiguous to each end of the tube and each of said transformers having their points of

zero potential in both their high and low tension windings connected together to each other.

13. A vacuum tube lighting system operated by sources of energy located contiguous to the opposite ends of the tube, respectively, and connected by a conductor joined to the centers of each of said sources.

14. In a vacuum tube lighting system, a tube having its exciting source of energy divided into sections located, respectively, at

opposite ends of said tube and joined to one another by a direct connection independent of that through the tube.

Signed at New York in the county of New ¹⁵ York and State of New York this 14th day of April A. D. 1908.
